UNITED STATES PATENT OFFICE.

JOHN C. PARKER, OF BALA, PENNSYLVANIA.

STEAM-GENERATOR.

1,205,656.

Specification of Letters Patent. Patented Nov. 21, 1916.

Application filed July 8, 1915. Serial No. 38,792.

To all whom it may concern:

Be it known that I, JOHN C. PARKER, a citizen of the United States, residing at Bala, in the county of Montgomery and State of Pennsylvania, have invented certain Improvements in Steam-Generators, of which the following is a specification.

My invention relates to steam generators having continuous circulating tubes and comprises, in its preferred form, a plurality of steam and water compartments, in combination with tubular coils having inclined sections and tubular connections between the top and bottom sections and the respective compartments.

A primary object of the invention is to provide a continuous tubular generator, or generator having continuous tubular coils, with an improved circulating system adapted for preventing the trapping of steam or air, said system comprising upflow bottom tubes having their upper ends connected directly with a steam collecting chamber, so that such tubes, which carry the baffles and are disposed directly over the fire, will start and maintain the circulation in its desired course, downwardly from the water chamber through the coils.

A further object is to provide the circulating system with inclined down flow tubes or coil sections combined with upflow bottom sections subject to the first effects and the highest heat of the fire.

The characteristic construction and the resulting improved functions of the invention will more fully appear by reference to the following description and the accompanying drawings in illustration thereof.

In the drawings, Figure 1 is a vertical sectional view taken longitudinally through a steam generator embodying my improvements; Fig. 2 is an irregular transverse sectional elevation of a part of the same; Fig. 3 is an irregular vertical sectional view taken longitudinally through a modified form of steam generator embodying the invention; and Fig. 4 is an irregular transverse sectional elevation of a part of the construction shown in Fig. 3.

The mechanism, as illustrated in the drawings, comprises the setting 1 containing the grate 2 and the drum 3 divided into a steam compartment 4 and a water compartment 5 separated by the partition 6 and communicating through the ports 7 and 8 therein, the part 7 being controlled by a

check valve 9 and the port 8 by a float valve 10.

In the form of the invention illustrated in Figs. 1 and 2, the water compartment 5 is connected by the nipples or short tubes 11 with junction boxes 12 respectively connected with the upper ends of pairs of inclined tubes 13. Junction boxes 14 connect the lower ends of the respective inclined tubes with the upper ends of succeeding inclined tubes 13, excepting the lowest tubes 13 which have their lower ends connected respectively with the lower ends of two inclined bottom tubes 13' by junction boxes 14'. Junction boxes 15 connect the upper ends of the respective pairs of superposed bottom tubes 13' and are connected by upcasts 16 with the steam compartment 4, above the water level. A baffle 17 is placed above the grate 2, between the lowest tubes 13 and the upper tubes 13', the tubes 13 being disposed one above the other and subject to the highest effect of the fire.

It will be understood that in the normal operation of this generator, water flows downwardly from the compartment 5 through the conduits 11, 12, 13, 14, and 14' to the lower ends of the conduits 13', through which and the conduits 15 and 16 it flows upwardly to the steam compartment 4. This form of the generator comprises single, one-tube wide, vertical elements, and consequently provides the maximum number of vertical elements and a high capacity for forcing. The inclination of the tubes facilitates the flow of steam and air from the upper tubes 13 to the compartment 5 and the lower tubes 13' to the compartment 4, when the boiler is standing over a slow fire, thus permitting the ready escape of air and steam from the tubes when they are standing full of water. Air or steam, thus permitted to flow freely back through the tubes 13 to the compartment 5, escapes from this compartment to the compartment 4 through the port 8 under control of the float valve 10, which, with the valve 9, controls communication between the compartments 4 and 5. The tubes 13 and 13' are preferably of the same diameter, with two rows of up-flow bottom tubes 13' though a single row of the latter tubes may be employed.

In the form of the invention illustrated in Figs. 3 and 4, the bottom of the drum 3 is connected by the short tube or nipple

17 with the junction box 18 which is connected with corresponding ends of parallel tubes 19. Horizontal junction boxes 20 connect the opposite ends of these tubes 19 in substantially horizontal pairs and vertical junction boxes 21 connect corresponding ends of outer superposed tubes of the respective elements in substantially vertical pairs, the elements being thus made two tubes wide. The lower tubes 19 have ends connected by junction boxes 21' with the upper ends of inclined down-flow tubes 19' whose lower ends are connected by junction boxes 20' with the lower ends of upflow tubes 19'', the upper ends of the latter tubes being connected by junction boxes 22 with upcasts 23 which discharge into the drum 3 above the water level.

A check valve 24 prevents reverse flow 20 through the tubes 19 and 19' to the drum 3 and a baffle 25 being placed between the tubes 19' and 19'' above the grate 2, the flow being laterally and downward through the elements comprising the tubes 19 and 25 19' and upwardly through the tubes 19'', which receive the highest heating effect.

It has been found desirable to use one upcast for several bottom tubes or to provide an upcast passage or passages connected with relation to the passages 30 delivering thereto, since by this relation the increased amount of steam carried by the upcast increases the differential head over what it would be with the upcasts equal 35 in cross-sectional area to the coils delivering thereto. This arrangement, moreover, tends to secure ample water in the bottom

tubes and consequent protection therefor, in addition to facilitating circulation.

Having described my invention, I claim:

1. In a steam generator, steam and water containing means, an upcast connected with the stem space of said means, a down-flow coil having an upper section connected with the water space of said means, a bottom section inclined upwardly in the direction of flow therethrough and having its upper end connected with said upcast, the lower end of the upper section discharging into the lower end of said bottom section, a baffle 50 between said bottom and upper sections, and means for applying primary heating action to said bottom section immediately beneath said baffle.

2. In a steam generator, steam and water 55 containing means, an upcast connected with the stem space of said means, a down-flow coil having an upper section connected with the water space of said means, a bottom section inclined upwardly in the direction of flow therethrough and having its upper end connected with said upcast, a downwardly inclined intermediate section higher than said bottom section and discharging through the lower end thereof to the lower end of 60 said bottom section, a baffle between said bottom and intermediate sections, and means for applying primary heating action to said bottom section immediately beneath said baffle.

In testimony whereof I have hereunto set my name this 3rd day of July, 1915.

JOHN C. PARKER.
